UNITED STATES PATENT OFFICE.

DAVID W. GARNER, OF ORME, TENNESSEE.

LOCK.

1,196,675.

Specification of Letters Patent. Patented Aug. 29, 1916.

Application filed May 19, 1916. Serial No. 98,599.

To all whom it may concern:

Be it known that I, DAVID W. GARNER, a citizen of the United States, residing at Orme, in the county of Marion and State of Tennessee, have invented new and useful Improvements in Locks, of which the following is a specification.

This invention relates to a lock especially adapted for securing hasps to staples.

10 The primary object of the invention is to provide a lock for the purpose described which may be advantageously used upon mail bags, although it is so constructed as to enable the lock to be used in connection 15 with the hasp and staple upon barn doors if found desirable.

Another object of the invention is to provide the lock with a spring controlled bolt which when moved to an unlocked position 20 by means of a key for this purpose may be held in such position by a spring finger carried by the casing and engageable therewith.

25 A further object of the invention is to so arrange the spring finger within the casing that when the bow of the staple is inserted within the casing, the spring finger will be released from engagement with the bolt and allow the spring which controls the same 30 to move the bolt to locked position.

A still further object of the invention is to provide the bolt with a spring pressed 35 tumbler connected with a spring controlled detent mounted to slide in the bolt and adapted to engage with a guide rib in the casing when the bolt is in locked position to prevent said bolt from being retracted by means other than a key designed for this purpose.

40 With these and other objects in view, the invention resides in the novel combination and arrangement of parts which will be hereinafter described and particularly pointed out in the claims.

45 The preferred embodiment of the invention has been illustrated in the accompanying drawing, although no restriction is necessarily made to the precise details of construction therein shown, as changes, alterations, and modifications within the scope 50 of the claims may be resorted to when desired.

Like characters of reference denote corresponding parts throughout the several views 55 in the drawing, in which:

Figure 1 is a side elevation of a lock con-

structed in accordance with the invention and showing the same connected with a staple to lock a hasp thereto. Fig. 2 is a view similar to Fig. 1 showing the casing 60 of the lock broken away. Fig. 3 is a plan view of the reversed side of the lock showing the casing broken away. Fig. 4 is a view similar to Fig. 3 and showing the bolt in retracted position. Fig. 5 is a vertical longitudinal sectional view on the line 5—5 of Fig. 4 showing the bolt held in a retracted position by means of the spring finger on the casing. Fig. 6 is a detail perspective view of the locking bolt removed from the casing. 70 Fig. 7 is a detail perspective view of the tumbler operated detent, and Fig. 8 is a side elevation of the key for retracting the locking bolt and operating the spring controlled tumbler.

75 Referring now to the drawing in detail, the numeral 1 designates the lock casing which is substantially rectangular in shape and comprises a bottom 2, end walls 3 and 4, sides 5, and a cover plate 6. The cover plate 80 6 has formed therein between its ends a key-hole 7 and is secured to the sides and end walls of the casing in any suitable manner. The bottom 2 of the casing has formed 85 therein an elongated and transversely extending opening 8 adjacent the end 3 of the casing and adapted to have passed therethrough the body of the staple indicated in Fig. 1 of the drawing by the numeral 9. The end wall 3 of the casing has formed 90 90 therein a vertically extending recess 10 opening out interiorly of the casing above the opening 8 in the bottom thereof. Partitions 11 and 12 extend transversely of the casing interiorly thereof and are spaced 95 from each other and from the end walls of the casing, said partitions being recessed between their ends, as at 13, with the recesses alining with each other to form a guide way for a locking bolt 14 which the partitions 100 support for sliding movement within the casing. A key stud 15 extends laterally from the inner face of the bottom 2 between the partitions 11 and 12 and is arranged adjacent a ward 16 also extending laterally 105 from the bottom 2. The locking bolt 14 which extends longitudinally of the casing is provided at one end with a head 17 adapted to be received in the recess 10 when the bolt is in locked position and has formed 110 thereon at its other end an extension 18 arranged below the partition 11 and inserted

within a coiled expansion spring 19 having an end bearing against the end wall 4 of the casing.

From the above described arrangement of the locking bolt within the casing, it will, of course, be understood that the spring 19 normally exerts tension on the bolt to move the head thereof above the partition 12 and into the recess 10.

10 The locking bolt 14 is recessed upon one side, as at 20, between the head 17 and extension 18 to form a shoulder 21 with which a bit 22 on a key 23 shown in Fig. 8 in the drawing is adapted to contact and move the locking bolt to retracted position against the influence of the spring 19. The locking bolt 14 is recessed for the greater portion of its length upon one side, as at 24, between the head 17 and extension 18 to form a shoulder 25, the bottom wall 26 of said recess being transversely channeled, as at 27, adjacent the shoulder 25.

25 A leaf spring 28 extends longitudinally of the recess 24 and has one end secured in a kerf upon the head 17 the other end of said spring being adapted to bear against a tumbler 29 pivotally connected with the bottom wall 26 of the recess 24, said tumbler having formed thereon at its free end a detent operating finger 30.

30 A detent 31 is arranged within the recess 24 and has its bottom face adapted to contact with the shoulder 25 and has formed in its upper face a recess 32 in which is received the operating finger 30 on the tumbler 29. The detent 31 is further provided upon one side with a rib 33 arranged in the transversely extending channel in the bottom of said recess whereby said detent may be supported by the shoulder 25 and guided transversely of the recess by the channel and rib 33 when the tumbler 29 is turned about its pivotal connection with the locking dog by the bit on the key 23.

45 One end of the detent 31 is normally held projected beyond the recessed side edge of the locking dog 17 by means of the tumbler 29 and spring 28 to engage with the partition 11 when the locking bolt is in locked position, said projecting end being rounded, as at 34, and contacting with one end of a leaf spring 35 carried by the upper face 36 of the tumbler 29 and which is arranged in the path of movement of the bit of the key, the spring 35 serving to hold the detent from being projected from within the recess 24 when the locking bolt is moved to locked position.

60 A spring finger 37 is secured to the cover plate 6 within the casing and arranged in the path of movement of the bow of the staple when passed through the opening 8 in the casing, the free end of said finger being received in a recess 38 in the head 17 of the locking bolt when said bolt is in locked

position and adapted to contact with an end on the head 17 when the bolt has been retracted by means of the key 23 and to hold said bolt in retracted position against the influence of the spring 19.

70 It will, of course, be understood that as the bow of the staple is passed through the opening 8 when the locking bolt is held in retracted position by the spring finger 37, the said finger will be disengaged from the end of the locking bolt to allow the spring 19 to move the bolt to a position between the arms of the staple in which an end on the head will be received in the recess 10 in the end wall 3 of the casing.

75 When it is desired to remove the lock from the staple as shown in Fig. 1 in the drawing, the key 23 is inserted through the key-hole in the cover plate 6 and engaged with the key stud 15. The key is now turned to cause the bit thereon to depress the free end of the tumbler 29, such movement imparting sliding movement to the detent 31 to remove its projecting end from contact with the partition 11. Further turning movement of the key will cause the bit thereon to engage with the shoulder 21 and slide the bolt to a position within the casing in which the upper end of the head 17 is below the bottom edge of the opening 8, at which time the end of the spring finger contacts with the end on the head and holds the bolt from upward movement and assists in ejecting the staple from within said opening.

80 The key may now be withdrawn from the casing and when it is desired to again apply the lock to the staple, the bow of the staple is positioned within the casing through the opening 8. As the bow of the staple is brought into contact with the spring finger 37, the same is released from the end of the head 17 allowing the spring 19 to move the locking bolt upwardly until an end on the head is received in the recess 10, at which time, the head will be between the arms of the staple and the curved end of the detent 31 projected beyond the recessed side edge of the locking bolt and in contact with the partition 11, thus preventing the locking bolt from being retracted by other means than the key 23.

85 90 95 100 105 110 115 120 125 130 From the foregoing description, taken in connection with the accompanying drawing, it is at once apparent that a lock has been provided for securing a hasp to a staple which is inexpensive of manufacture, yet highly efficient in use.

Having thus described the invention, what is claimed as new, is:

1. A device of the class described comprising a casing having a slot therein to receive the bow of a staple, a key operated bolt arranged within the casing and having an end to be received between the arms of the staple when the bolt is in locked posi-

- tion, a key operated tumbler carried by the bolt, and a detent mounted to slide on the bolt and arranged in the path of movement of the tumbler.
5. 2. A device of the class described comprising a casing having a slot therein to receive the bow of a staple, a key operated bolt within the casing having a shoulder extending transversely thereof, a detent 10 ranged upon the shoulder and movable transversely of said bolt, a key operated and spring controlled tumbler carried by the bolt and operatively engaged with the detent to hold one end thereof extended beyond the bolt when the same is in locked 15 position, and a member on the tumbler contacting with the detent adapted to limit the sliding movement of the detent in one direction under the influence of the tumbler.

3. A device of the class described comprising a casing having a slot therein to receive the bow of a staple, partitions within said casing, a key operated locking bolt mounted for sliding movement within said partitions and having an end adapted to 25 extend beyond said slot when said locking bolt is in locked position, a key operated and spring controlled tumbler carried by the bolt, and a detent mounted to slide in the bolt and operatively connected with the 30 tumbler whereby said detent may be held in contact with one of said partitions when the locking bolt is in locked position.

In testimony whereof I affix my signature.

DAVID W. GARNER.
